(57) **CLAIM**

The ornamental design for a wall mounted bottle filler, substantially shown and described herein.

DESCRIPTION

FIG. 1 is a left front perspective view of a wall mounted bottle filler showing our new design;
FIG. 2 is a front view of the wall mounted bottle filler of FIG. 1;
FIG. 3 is a back view of the wall mounted bottle filler of FIG. 1;
FIG. 4 is a left view of the wall mounted bottle filler of FIG. 1;
FIG. 5 is a right view of the wall mounted bottle filler of FIG. 1;
FIG. 6 is a top view of the wall mounted bottle filler of FIG. 1; and,
FIG. 7 is a bottom view of the wall mounted bottle filler of FIG. 1.

1 Claim, 7 Drawing Sheets
